UNITED STATES PATENT OFFICE.

CHARLES H. ANDERSON, OF CINCINNATI, OHIO.

PASSENGER-CAR.

1,148,001.

Specification of Letters Patent. Patented July 27, 1915.

Application filed January 12, 1915. Serial No. 1,858.

To all whom it may concern:

Be it known that I, CHARLES H. ANDERSON, a citizen of the United States, and a resident of Cincinnati, in the county of Hamilton and 5 State of Ohio, have invented certain new and useful Improvements in Passenger-Cars; and I do hereby declare the following to be a full, clear, and exact description of the invention, such as will enable others skilled in 10 the art to which it appertains to make and use the same.

My invention relates to an improvement in passengers cars.

In steel car construction, and particularly 15 those embodying metal side posts, it is necessary to provide numerous anchorage blocks and cleats to form supports for the curtain brackets; for the conduits carrying bell, light and other wires from end to end of the 20 car, and also for the ornamental wood work forming the window curtain box, and these anchorage blocks or cleats which are usually of wood, are all applied after the frame of the car has been erected.

25 The object of this invention is to do away with the numerous parts formerly used, and provide a standard attachment that can be applied to the side posts before the latter are assembled in the car, thus making the 30 side posts interchangeable and each carrying, as an integral part, the supports for all the various parts of the curtain box and the parts within the latter that have heretofore been attached to the post after the car frame 35 has been erected, and my invention consists in the parts and combinations of parts as will be more fully described and pointed out in the claims.

In the accompanying drawings, Figure 1 40 is a view in section through one side of a car showing my improvement applied to a side post thereof. Fig. 2 is a view in perspective of a section of a side post showing my improvement attached to same and Fig. 45 3 is a view in section on the line $x-x$ of Fig. 1.

1 represents the side post of a car, 2 the eaves or name plate and 3 the window curtain box. The posts at the sides of the car 50 are all alike, and are in the present instance T-shape with the flange portion presenting outwardly for the attachment of the side and eaves or name plate.

Secured to the inner edge of the web of 55 each side post is the bracket 4, preferably made of sheet metal rectangular in shape.

The top end of the plate forming the bracket 4 is bent inwardly as at 5 and downwardly as at 6, the lower free end of the downwardly bent portion 6, being secured to the body 1 60 of bracket by the bolt 7 carrying the spacing sleeve 8, thus forming a pocket for the reception of the pipe or conduit 9 which may carry the bell, light and other wires from one end of the car to the other, the said 65 conduit being supported on the sleeves 8. The body of the bracket 4 is slotted in rear of said pocket and the metal released by slotting is turned outwardly at right angles so as to rest against the web of side post and 70 be secured to the latter by a bolt or rivet.

The plate 4 is provided at its side edges intermediate its ends with the ears 10 which are bent inwardly into parallel position, and forms brackets for the support of window 75 curtain rollers, one of said brackets being slotted as at 11 for the reception of the angular end of the spring rod of one curtain roller, and the other with a hole 12 for the reception of the fixed spindle of the next adjacent roller. The side posts form the side frames for the windows, hence each bracket 4 carries two ears or brackets 10 for supporting the adjacent ends of the two curtains at 80 the opposite sides of the side post. 85

The lower portion of the plate 4 is bent slightly outwardly a distance equal to about the thickness of said plate, and is slotted centrally as at 13 so as to permit the plate to fall back so that its inner face will be approximately flush with the inner edge of the web of the side post, the plate being welded at the edges of said slot to the web of the side post, so as to permanently unite the plate 4 to the post, this being done during 90 the manufacture of the post and before it is placed in position in the car. The plate is also provided adjacent its lower edge with the laterally projecting ears 14 having holes therein, and the extreme lower slotted end 15 of the plate, is bent outwardly at right angles, so as to rest against the opposite faces of the web of the post, the said bent ends each having a screw hole. The downwardly bent end 6 of the plate is also provided with a threaded hole, the wall of which is thickened for the attachment of a screw rod which supports the package rack at the top of the sides of the car. 95 100 105

Secured to the underside of the bent ends 110 15 is a bronze plate 16, which supports the base 17 of the curtain box, and to which said

base 17 is secured by screws. Secured on the top 5 of the plate or bracket 4, is the wood block 18 the front or face 19 of said box being secured to said base 17 and block 18. 5 Located within the box and secured by screws to the ears 14 of the plate or bracket 4, is the wood strip 20 carrying the electric wires 21 leading to the bell which is actuated by the push buttons located in the usual 10 position.

With this construction it will be seen that with the plates or brackets 4 properly secured to the posts, the building of the curtain roller box becomes a comparatively simple 15 matter, as the location for the several parts of the same is fixed by the brackets 4, thus doing away altogether with the measurements which were necessary in locating the anchorage blocks, and in the drilling 20 necessary to secure said blocks in place. As the posts are alike, and the brackets will occupy the same relative position, it will be seen that the posts are interchangeable and when assembled the brackets 4 will all be in 25 proper position to receive the curtain rollers and the housing members of the box.

It is evident that many slight changes might be resorted to in the relative arrangement of parts shown and described without 30 departing from the spirit and scope of my invention. Hence I would have it understood that I do not wish to confine myself to the exact construction and arrangement of parts shown and described but

35 Having fully described my invention what I claim as new and desire to secure by Letters-Patent, is:—

1. In steel car construction, the combination of a metal side post, a curtain box and 40 a metal bracket rigidly secured to the post, the said bracket having supports for the attachment of supporting members of the curtain box, conduit for wires and ears for supporting the adjacent ends of two curtain 45 rollers.

2. In steel car construction, the combina-

tion of a metal side post, a curtain box and a bracket secured to the post and provided with a housing for a conduit, two ears for supporting the adjacent ends of two curtains 50 and flanges for the attachment of members of the window curtain box.

3. In steel car construction, the combination of a metal side post, and a bracket permanently secured to the latter and provided at its upper end with a housing for a conduit, at its lower end with flanges for the attachment of the base member of a window curtain box, and intermediate its ends with ears for supporting the adjacent ends of two 55 curtain rollers.

4. In steel car construction, the combination of a metal side post T-shape in cross section and a bracket permanently secured against the free edge of the web of said post, 65 the upper end of said bracket being bent inwardly and downwardly to form a housing for a conduit, the lower end bent at right angles to the body for the attachment of the base member of the window curtain box, and provided at its side edges intermediate its 70 ends with ears for supporting the adjacent ends of two curtain rollers.

5. In steel car construction, the combination of a metal side post T-shape in cross 75 section and a metal bracket permanently secured to said post, the said bracket having a housing at its upper end for a conduit, bent lower end for the attachment of the base member of a curtain box, ears adjacent the 80 lower end for the attachment of a strip carrying the electric bell wires, and inwardly projecting ears for supporting the adjacent ends of two curtain rollers.

In testimony whereof, I have signed this 85 specification in the presence of two subscribing witnesses.

CHARLES H. ANDERSON.
